CLAIM

The ornamental design for a lamp for outdoor use, as shown and described.

DESCRIPTION

FIG. 1 is a front perspective view of the lamp for outdoor use of the present invention showing my new design, with the dotted lines depicting portions of the lamp that form no part of the claimed design;

FIG. 2 is a front view thereof;

FIG. 3 is a right view thereof;

FIG. 4 is a left view thereof;

FIG. 5 is a back view thereof;

FIG. 6 is a top view thereof; and,

FIG. 7 is a bottom view thereof.
